US00D765613S

(12) **United States Design Patent** (10) **Patent No.:** **US D765,613 S**
Wolf (45) **Date of Patent:** **** Sep. 6, 2016**

(54) **HOUSING FOR ELECTRIC AND ELECTRONIC COMPONENTS**

(71) Applicant: **INTER CONTROL Hermann Kohler Elektrik GmbH & Co. KG, Nuremberg (DE)**

(72) Inventor: **Roland Wolf, Hersbruck (DE)**

(73) Assignee: **INTER CONTROL Hermann Kohler Elektrik GmbH & Co. KG, Nuremberg (DE)**

(**) Term: **14 Years**

(21) Appl. No.: **29/468,725**

(22) Filed: **Oct. 2, 2013**

(30) **Foreign Application Priority Data**

Apr. 3, 2013 (EM) 002213207

(51) LOC (10) Cl. **13-03**

(52) U.S. Cl.

USPC **D13/184**

(57) **CLAIM**

The ornamental design for a housing for electric and electronic components, as shown and described.

DESCRIPTION

FIG. 1 is a perspective view of a housing for electric and electronic components showing my new design; and, FIG. 2 is a bottom perspective view thereof.

1 Claim, 2 Drawing Sheets

FIG. 2
